UNITED STATES PATENT OFFICE.

LEWIS A. STAVE, OF CHICAGO, ASSIGNOR OF FIVE-EIGHTHS TO ANDREW B. SPURLING, OF ELGIN, ILLINOIS.

FIRE-ARM.

SPECIFICATION forming part of Letters Patent No. 364,446, dated June 7, 1887.

Application filed October 10, 1885. Serial No. 179,460. (No model.)

To all whom it may concern:

Be it known that I, LEWIS A. STAVE, a citizen of the United States, residing in Chicago, county of Cook, and State of Illinois, have invented certain new and useful Improvements in Fire-Arms, of which the following is a specification.

This invention relates to improvements in fire-arms in which a supplemental barrel has its breech opened and closed by a sliding of its barrel upon the main barrel, and in which the firing mechanism is connected with and actuated by the firing mechanism of the main barrel, all as set forth in Letters Patent No. 15 234,213, granted me September 14, 1880.

The prime object of this invention is to dispense with any mechanical connection between the firing mechanism of the main barrel and a supplemental barrel, and to have the trigger 20 of the supplemental barrel at a point forward of the trigger of the main barrel in a convenient position for manipulation without mar- 25 ring the effects of the gun, and to attain these objects by devices which may be conveniently attached to any ordinary breech-loading fire-arm.

A further object is to have the breech-piece of the supplemental barrel constructed in such a manner that it is adapted to carry the firing 30 mechanism and to be conveniently attached to the stock of an ordinary breech-loading fire-arm, to have a connection between said sup- 35 plemental breech and the sliding barrel inde- 40 pendent of and outside of the plane of the main barrel, and likewise between the sliding barrel and main barrel, whereby the longitudinal 45 groove of the main barrel is dispensed with, and, finally, to have several parts for actu- 50 ating and firing the supplemental sliding barrel constructed and arranged so as to promote 55 their simplicity of construction and convenience of manipulation, all as hereinafter de- 60 scribed, and shown in the accompanying draw- 65 ings, in which—

Figure 1 represents a detail side elevation of a fire-arm embodying my invention; Fig. 2, a similar view, with the breech of a sup- 70 plemental sliding barrel in a partly-open condition; Fig. 3, a bottom plan view of the same;

Fig. 4, a detail longitudinal section of the supplemental barrel and its firing mechanism with the trigger and its actuating-spring shown partly in side elevation; Fig. 5, a side elevation of a modification of the lever-connection between the sliding connection and its breech, 55 and of the device for setting the firing-pin and the trigger, and also of the trigger; Fig. 6, a bottom plan view of the same.

Similar letters of reference indicate the same parts in the several figures of the drawing. 60

The stock A, the locking mechanism B, and the main barrel C of the fire-arm may be of the ordinary construction common to breech-loading fire-arms, whether rifles or single or double barreled shotguns. On the forward 65 end of the stock A is secured, in any convenient manner, as by set-screws, a plate, a, which is the end piece, and a rigid part of a tubular butt-piece, b, which, toward its forward end, is, by a dovetail block, c, secured to the main 70 barrel C of the gun.

At suitable intervals of the main barrel, and by dovetail projections d, are secured eyes e, forming guides and bearings for the supplemental barrel f to slide in, which barrel may 75 be rifled when attached to a shotgun or rifle, or, if desired, be a shotgun-barrel when at- 80 tached to the latter, though in practice it is designed to be a rifle-barrel of small bore.

Pivoted on the block c, or to the tubular 80 breech, is a hand-lever, g, connected at a point between its extremities with the sliding barrel by link h, and in such a manner that when the breech of the supplemental barrel is closed the free end of the lever will lie at a point inter- 85 mediate the main and supplemental barrels, as shown at Fig. 1, and when swung down- 90 wardly from this position, as shown in Fig. 2, will actuate and expose the breech of the sup- 95 plemental barrel to such an extent that when the lever is swung to the limit of its forward stroke said barrel will be in position to receive or discharge a shell or cartridge.

The forward end of the tubular butt-piece is closed by a butt block or plug, i, preferably 95 screwed into the butt-piece, but may be se- 90 cured in any other desired manner and pro- 93 vided with a perforation, i', constituting a pas-

sage for the firing-pin, projected therethrough to explode the cap of the shell in the sliding barrel when in its operative position.

- The under side of the tubular butt-piece is 5 provided with an elongated slot, *k*, over which works a sliding catch-piece, *l*, rigidly connected with the firing-pin by a projection or stud, *m*, said catch-piece and the firing-pin being actuated to propel the firing-pin forward 10 to explode the cap of the shell by a spring, *n*, confined between the lug *m* and the plate *a*, and coiled about a rearwardly-projecting end of the firing-pin, as clearly shown in Fig. 4.
- Pivoted midway of its length on the stock 15 *A*, toward the forward end of said stock and in a plane parallel with the length thereof, is a trigger, *o*, provided at its forward end with a catch or projection, *p*, adapted to engage a similar projection, *p'*, on the catch-piece *l*, and 20 actuated by an expansion-spring, *q*, seated in the stock and bearing against the inner face of the trigger, so as to automatically lock it with the catch-piece when the firing-pin is retracted and set for exploding a cap.
- 25 In practice it is proposed to have the trigger so set in the stock that it shall not project outside thereof, and hence not liable to catch upon the clothing or anything else so as to cause an accidental firing of the supplemental 30 barrel or injury to any of its supplemental parts.

On the forward end of the tubular butt-piece is secured a shell-extractor, *r*, which projects over the butt-block, the barrel being 35 beveled or notched for this purpose, and the shank of the extractor is of spring metal, so that the extractor may yield sufficiently to pass over the flange of the shell and catch upon the inner side thereof as the sliding bar- 40 rel is being seated against the butt-block.

In operation the barrel is thrown open by swinging the lever *g* downwardly from the position shown in Fig. 1, and either before or after the barrel is closed upon its butt-piece 45 the firing-pin is set by retracting the catch-piece until engaged and locked in its retracted position by the trigger. As the barrel is being forced upon its seat, the extractor by its spring action rides over and engages the shell- 50 flange, so that after firing the load and while again throwing open the sliding barrel the extractor will hold the shell against the butt-piece until the barrel has passed beyond the forward end of the shell, when the shell may 55 be conveniently released from the extractor and removed.

In Figs. 5 and 6 I have shown as a modification and another form of the invention before described a bifurcated lever, *s*, the arms 60 of which project upon each side of and are pivoted to the butt-piece, each arm being connected by corresponding links, *t* *t*, with the sliding barrel, and the free end of the lever being concaved on its under side to conform 65 to and embrace the periphery of the butt-piece.

Instead of securing the sliding barrel to the main barrel by the dovetail blocks before described, it may be secured by clips *t*, secured by screws or soldered to the main barrel.

In the construction shown in Figs. 5 and 6 opposing sides of the stock are provided with elongated slots, through which project arms *u*, which are connected with the firing-pin in the same manner as in the first instance, while the trigger is concealed within the stock except its rearwardly-projecting end *v*.

The construction shown in Figs. 5 and 6 is essentially the same as in the preceding figures, except that the catch-piece has duplicate projections or finger-pieces for setting and that the trigger is substantially concealed.

The first-described construction is preferred, however, because it dispenses with any necessity of grooving out or cutting the stock, and therefore involves less labor and skill in the attachment of the supplemental barrel and its firing mechanism to the ordinary fire-arm.

So far as I now know I am the first to provide a special trigger forward of the breech of the main barrel and having no mechanical connection with the firing mechanism of said barrel, and my invention is therefore not limited to the location of said supplemental trigger at any particular point between the supplemental barrel and the trigger of the main barrel, or to the employment of such a trigger in connection with a supplemental barrel opened only by a sliding movement thereof, for in this respect my invention includes, broadly, a supplemental barrel and an independent trigger therefor at any point between said barrel and the main barrel. Nor is my invention limited to the special form of link- 90 and lever connection between the supplemental barrel and its breech, for it includes, broadly, a lever pivoted to one of said members and connected directly with the other member by a pivoted link, whether said barrel slides or swings upon a pivot to throw it 95 open.

Having described my invention, what I claim, and desire to secure by Letters Patent, is—

1. The main barrel and the supplemental barrel, in combination with a trigger for the supplemental barrel, located at a point forward of the breech of the main barrel, substantially as described.
2. The main barrel and the supplemental barrel, in combination with a trigger for the supplemental barrel forward of and having no mechanical connection with the trigger of the main barrel, substantially as described.
3. The supplemental barrel, the firing-pin thereof, and a sliding catch-piece parallel with and rigidly secured to the firing-pin, and a pivoted trigger engaging said sliding catch-piece, substantially as described.
4. The tubular butt-piece, the firing-pin, and a spring for actuating said pin within said butt-piece, in combination with a sliding

catch-piece parallel with and rigidly secured to the firing-pin, and bearing upon the butt-piece, and a trigger for engaging said catch-piece, substantially as described.

5. The supplemental barrel and the butt-piece thereof, in combination with a swinging lever pivoted to the side of the butt-piece,

and a link pivoted to the side of the barrel and said lever, substantially as described.

LEWIS A. STAVE.
